PEDAL LOCKING MEANS FOR AUTOMOBILES

Filed Sept. 27, 1924

2 Sheets-Sheet 2

Inventor:
Harold Thorne,
By his Attorney, Leo F. Niarch

UNITED STATES PATENT OFFICE.

HAROLD THORNE, OF NEW YORK, N. Y.

PEDAL-LOCKING MEANS FOR AUTOMOBILES.

Application filed September 27, 1924. Serial No. 740,204.

To all whom it may concern:

Be it known that I, HAROLD THORNE, a subject of the King of England, and a resident of the borough of Manhattan, city, 5 county, and State of New York, have invented certain new and useful Improvements in Pedal-Locking Means for Automobiles, of which the following is a specification sufficient to enable those skilled in the 10 art to which the invention appertains to utilize the same.

This invention is supplementary to that set forth in my concurrent application Ser. No. 725,132, filed July 10th 1924 and in like 15 manner, while applicable to automobiles generally in a broad sense, my present pedal locking device, considered in a unitary sense, is designed primarily and especially for use in conjunction with automobiles of 20 the Ford type, and is so illustrated and described herein—the object being to afford simple, inexpensive, but effective and positive means for securely clasping and holding the pedals of such a car against clandestine movement, and the combination 25 consisting in the specific construction, combination and arrangement of parts and appurtenances described and claimed, a distinctive feature being the provision of super-imposable, interlocking clasp plates 30 individually hinged to the foot board of the car and adapted to engage with the sides of the pedal slots of said foot board in such manner as to prevent movement of the 35 pedals while such clasp plates are in superposed position, thereby safe-guarding the car against surreptitious manipulation or movement, all as hereinafter fully set forth.

40 In the accompanying drawings I illustrate a practical embodiment of the essential features of my invention as applied to the foot board of an automobile of the Ford type, although I do not limit myself to the identical form and construction of parts 45 and appurtenances shown herein by way of exemplification, since changes in minor details may be made, and equivalent mechanical expedients resorted to with like results, 50 and without departing from the spirit and intent of my invention in this respect.

With this understanding:—

Fig. 1, represents diagrammatically the location and application of my complemen-

tary pedal clasp plates on the foot board of 55 a car of the character designated;

Fig. 2, is a sectional elevation, upon a larger scale, showing the face of the foot board and the pedals, with my pedal clasp plates in functional position; 60

Fig. 3, is a sectional side elevation of the parts as shown in Fig. 2;

Fig. 4, is a view of the upper side of a portion of the foot board, showing the pedal slots without the pedals, and with my lock 65 plates opened up;

Fig. 5, is a similar view showing my complementary clasp plates in position on the foot board, the pedals being shown in cross-section; 70

Fig. 6, is a face view, upon a larger scale, of my pedal clasp plates in closed position;

Fig. 7, is a section thereof, taken upon plane of line 7—7, Fig. 6;

Fig. 8, is a front elevation of the upper 75 clasp plate;

Fig. 9, is an end view thereof;

Fig. 10, is a front elevation of the lower clasp plate;

Fig. 11, an end view thereof. 80

The foot board B, formed with the usual three parallel pedal slots, b', for the gear pedal p', b² for the reverse pedal p², and b³, for the brake pedal p³, said slots and pedals being of the usual construction, and functioning as heretofore in a manner well known in the prior state of the art, so that description of operation is unnecessary in this respect, my invention relating solely to means for securely holding said pedals in 85 prescribed positions assumed thereby when the car is at rest. 90

To this end my present contrivance consists of two co-related complementary clasp plates,—i. e. a base or upper plate A, hinged to and adapted to rest directly upon the upper side of the foot board B, and a lower plate C, also hinged to the foot board B, and adapted to fit and overlap in part the upper plate A, as shown more particularly 100 in Figs. 6 and 7, of the drawings.

The two clasp plates A and C, are releasably connected in locked relationship by means of a lock L, preferably of the Yale type, or the equivalent thereof, the lock being mounted on one plate, and its bolts l, l, being engagable with mortises m, m, in the other plate as may be found most 105

expedient. In the particular arrangement shown in the drawings the lock L, mounted on the upper plate A, and bolts l, l, are engageable with mortises m, m, formed for the purpose in the plate C.

- 5 The clutch plates A and C, may be hinged to the foot board by any desired or suitable mechanical expedient. As shown by way of exemplification, knuckle plates K, 10 K, are attached to the underside of the foot board B, and are formed with knuckle tongues k, k, protruding through the pedal slots b', b², b³, as indicated more particularly in Figs. 4 and 7, of the drawings.
- 15 The upper plate A, is formed with recesses a', a², a³, coincident with the pedal slots b', b², b³, in the foot board B, and in an analogous manner the lower plate C, is recessed, as at c', c², c³, and coincident with 20 said pedal slots b', b², b³, the edges of said recesses, when the clutch plates A, C, are closed upon the foot board B, locking the pedals against movement substantially as and for the purpose set forth in my afore- 25 said concurrent application Ser. No. 725, 132,—it being understood that any similar combination and arrangement of recesses or offsets on the clutch plates for engagement with the pedals may be resorted to with like 30 result.

The clutch plates A, C, when opened up as shown in Fig. 4, of the drawings, do not impede in any way the action of the pedals in the usual manner.

What I claim as my invention and desire 35 to secure by Letters Patent, is:—

1. In pedal locking means, a foot board, two co-related opposed complementary clasp plates hinged at their outer edges to said foot board to fold bodily toward each other 40 and to overlap in folded position, said clasp plates being recessed upon adjacent edges to engage and hold the pedals in prescribed position, and means extended lengthwise of 45 said plates and engageable in opposed lateral mortises in one of said plates.

2. In pedal locking means, a foot board, two co-related opposed complementary clasp plates hinged along their outer edges to said foot board to fold bodily toward each other 50 and to overlap at their adjacent edges in folded position, said clasp plates being recessed in adjacent edges to engage and hold the pedals in prescribed position, and means centrally disposed on one of said clasp plates 55 and extended lengthwise of the same and extended across adjacent recesses and engageable in opposite lateral mortises in one of said plates.

HAROLD THORNE.
